BROOCH OR THE LIKE

Louis Kramer, New York, N. Y., assignor to Kramer
Jewelry Creations, Inc., New York, N. Y.

Application August 24, 1954, Serial No. 32,003

Term of patent 3½ years

(Cl. D45—19)

Fig. 1

To all whom it may concern:

Be it known that I, Louis Kramer, a citizen of the United States of America, residing in New York city, county of New York, and State of New York, have invented a new, original, and ornamental Design for a Brooch or the like, of which the following is a specification, reference being had to the accompanying drawing, forming part thereof.

Fig. 1 is a plan view of a brooch or the like, showing my new design.

Fig. 2 is an edge view thereof.

I claim:

The ornamental design for a brooch or the like, substantially as shown.
